FILLING VALVE

Charles E. Kerr, Hoopeston, Ill., assignor to Food
Machinery Corporation, San Jose, Calif., a cor-
poration of Delaware

Application July 21, 1937, Serial No. 154,798

15 Claims. (Cl. 226—124)

This invention relates to filling valves of the type used for filling liquids into containers such as cans or the like, and is concerned more particularly with an improved valve of this type which can be used for filling under pressure, under vacuum, or with an open tank.

It is a general object of the invention to provide an improved filling valve of a simple and economical construction which provides for efficient operating characteristics over an increased operating life as compared with known valves.

Another object of the invention is to provide an improved filling valve which can be adjusted easily to take up wear, and thereby provide for a long operating life with maximum efficiency.

Another object of the invention is to provide an improved filling valve which is constructed to provide a non-foaming filling operation and to prevent after-drip.

Other objects of the invention will be apparent from the following detailed description of a preferred embodiment thereof, with reference to the accompanying drawings, in which:

Fig. 1 is a vertical sectional view through the valve and a part of the filling tank on which the valve is mounted, taken through the center axis of the valve slide. The valve is shown in open position for filling operation.

Fig. 2 is a fragmentary elevational view of a part of the valve slide as indicated by the line 2—2 in Fig. 1.

Fig. 3 is a horizontal section through the valve and is taken in planes indicated by the line 3—3 in Fig. 1.

Fig. 4 is a fragmentary sectional view similar to Fig. 1, but showing the valve parts in the closed position thereof.

The filling valve of my invention is illustrated in connection with a conventional type of filling machine of which only fragmentary parts are shown, including the tank 10 and a cam lift plate 11, a can 12 being shown in operative position between the lift plate 11 and the valve. This type of machine operates to periodically open and close the filling valve by raising a can or other container into contact with the valve slide to open the valve by lifting the slide and to close the valve when the slide is lowered. Machines of this general type are well-known and if further description of the complete machine is desired, reference may be had to the patent to Thompson, No. 1,355,015, dated October 5, 1920.

In the embodiment of the invention selected for illustration, the valve comprises generally a valve body 16 which is secured on the tank 10

and a valve slide 17 which is slidably mounted in the body 16 and is spring-urged to its lower valve closing position. Preferably, the valve body 16 and the valve slide 17 are provided with planar faces engaged as at 18 and into which the various filling and vent passages through the slide and the body open.

The valve body 16 is provided with a flat face 21 which engages and is secured against suitable pads 22 on the tank 10, by means of apertured fastening screws 23 which extend through suitable apertures in the tank 10 and are threaded in the valve body 16, whereby the fastening means also provides part of the passages from the valve to the tank or to the atmosphere.

The valve slide 17 is provided at the top with an upwardly projecting rod or guide 26 which extends through an apertured overhanging flange 27 of the body 16 and has a head 28 for engagement with the top of the flange 27 to limit the lowered position of the valve slide with respect to the valve body toward which position the valve slide is urged by a spring 29 compressed between the flange 27 and the top of valve slide 17. The engaged planar faces of the valve body and the valve slide are maintained in close cooperation by means of U-shaped bracket 31 secured to the sides of the valve body 16 by suitable fastening screws as seen most clearly in Fig. 3, and extending around the valve slide 17, being threaded to receive adjusting screw 32 having a pressure plate 33 mounted freely on the end thereof for engagement with a flat surface 34 of the valve slide. A lock nut 36 is provided to maintain the adjusted position of the screw 32 and the pressure plate 33 with respect to the slide 17.

Thus, the valve slide is mounted for vertical movement relative to the valve body during operation of the valve, and can be adjusted transversely of the direction of its operative movement to maintain the close cooperative relation between the engaged surfaces of the valve slide and the valve body.

At its lower end, the valve slide 17 (Fig. 1) is threaded to receive can collar 41 providing a seat for a rubber can lift ring 42. By adjusting the collar 41, relative to the slide 17, the time at which a can 12 will engage the ring 42 to lift the valve slide upwardly can be varied to thereby vary the amount of fill as will be apparent hereinafter.

As previously stated, the valve body and the valve slide are provided with respective filling and vent passages for controlling the flow of

liquid from the tank into a can. The valve body has a filling passage 51 formed therein and opening through passage 52 into the bottom of the tank 10, whereby liquid can flow from the tank 5 through the passages 52 and 51 into an enlarged chamber 53 formed at the upper end of an annular passage 54, extending downwardly through the valve body around a conduit 56 threaded in the valve body and having a bell shaped or conical lower end 57 permanently spaced from a similarly formed wall 58 of the valve slide.

The valve body 16 is provided with a vent passage 63 for communication with a vent passage 62 formed in the valve slide 17 and extending downwardly through the conduit 56. The body vent passage 63 registers with the slide vent passage 62 in the lowered or valve closing position of the slide shown in Fig. 4, and if no venting is desired in this position as later explained, the passage 63 may be closed as by a screw plug 64, as shown in Fig. 3.

The valve body is also provided with a vent passage 61 which opens into the screw connection 23 which receives an elbow 66 mounting a vent pipe 67 which extends upwardly within the tank and above the level of liquid therein. Vent passage 61 communicates with the slide vent passage 62 in the raised position of the valve slide as shown in Fig. 1. For certain operations, the lower end of vent passage 62 may be closed by a bell shaped float 68 which is removably mounted by lugs 69 in operative relation with the lower face of bell shaped portion 57 of the conduit 56 and has a central semi-spherical extrusion 71 for seating in and closing the lower end of passage 62 in response to the rising level of the liquid in the can. The valve body is also provided with a vent passage 76 communicating with the opening in lower fastening screw 23, and which in the lower position of the valve slide communicates with chamber 53, plug 77 being provided to close the passage 76 during certain operations.

The operation of the valve will now be described in connection with the various different types of filling which can be effected thereby.

When filling under pressure, i. e., when the pressure in the tank is maintained above atmospheric pressure, the screw plugs 64 and 77 and float 68 are all mounted in place as shown in the drawings. Assuming the valve to be in the position shown in Fig. 4, when a can is brought up against sealing ring 42 and lifts the valve slide to the position shown in Fig. 1, the passage 62 communicates with the vent passage 61 of the body 16 before the filling chamber 53 communicates with the filling passage 51. As seen most clearly in Fig. 2, while the passage 62 and chamber 53 have ports of the same cross sectional area, their contour is different to provide a longer vertical opening in the vent passage than in the filling passage. This allows the pressure of the tank to be transferred to the container so that the pressures are equalized before the filling operation starts. As the valve slide continues to move up, filling chamber 53 registers with filling passage 51 of the valve body and a gravity flow of liquid starts from the tank through passage 51, chamber 53 and annular passage 54 over the bell shaped portion 57 and out against the walls of the can as indicated by the arrows in Fig. 1, this type of discharge providing a non-foaming operation. At the same time the air in the container is transferred back to the tank through the vent passages 62, 61, elbow 66 and vent pipe 67.

When the liquid in the container reaches the float 68, it lifts the float upwardly to seat extrusion 71 in the lower end of passage 62 and stop the flow of air from the container and consequently the flow of liquid from the tank into the container.

At this time, the can goes away from the valve slide and permits the return thereof to the position shown in Fig. 4, where the upper ends of the passages in the valve slide are all closed.

It will be noted that the enlarged chamber 53 at the top of the annular filling passage 54 insures an even distribution of liquid in the passage, so that at its lower end an unbroken circular curtain of liquid will be discharged. Also, the angular relation of the bell shaped end 57 over which the liquid is discharged to the wall of the can is such that the liquid will strike the can wall at an acute angle to prevent foaming.

The operation of the valve when filling under vacuum, i. e., when the pressure in the tank is maintained below atmospheric pressure, is similar to the operation when filling under pressure, but the valve is adapted for this operation by removing the float 68 and the plugs 64 and 77. The removal of the plugs 64 and 77 affects the operation by releasing the liquid in the vent passage 62 and filling passage 54 respectively, into the can as the valve slide moves to the valve closing position thereof to prevent after-drip, and also by relieving the vacuum so that the can moves away from the valve easily.

When using the valve in filling from an open tank, the valve is conditioned as described in filling under vacuum and operates in a similar manner.

While I have shown and described my invention as embodied in a preferred form, it will be understood that the invention is capable of variations and modifications from such preferred form, and, its scope, therefore, should be limited only by the scope of the appended claims.

I claim:

1. In a valve for filling cans or the like by a gravity flow of liquid from a tank, a valve body having a flat face, filling passage means leading from said face to said tank, vent passage means leading from said passage to said tank and terminating above the level of liquid therein, a valve slide movably connected to said valve body and having a flat face for cooperative sliding engagement with said body face, filling passage means extending from the lower end of said valve slide to the flat face thereof, vent passage means extending from the lower end of said valve slide to the flat face thereof, spring means urging said slide downwardly with respect to said body to maintain the respective filling and vent passages out of communication, a can lift ring on said valve slide for engagement by a can to effect lifting of said slide to establish communication between the respective similar passage means of said valve slide and said valve body, other passage means in said body for communicating with said vent and filling passages of said slide in the valve closing position of said slide, and means for selectively opening said other passage means to the atmosphere.

2. In a filling valve, a valve body having a flat face into which respective vent and filling passages open, a valve slide movably connected to said valve body having a flat face for sliding engagement with said body face and having respective vent and filling passages opening into the face thereof for simultaneous registration

with said body passages in one adjusted position of said slide relative to said body, said vent passages having a longer dimension in the direction of relative movement between said body and said slide than said filling passages, whereby the vent is established before a filling operation begins.

5. In a filling valve, a valve body having a flat face into which respective vent and filling passages open, a valve slide movably connected to said valve body having a flat face for sliding engagement with said body face and having respective vent and filling passages opening into the face thereof for simultaneous registration with said body passages in one adjusted position of said slide relative to said body, said respective vent and filling passages having substantially the same cross-sectional area and said vent passages having a longer dimension in the direction of relative movement between said body and said slide than said filling passages, whereby the vent is established before a filling operation begins.

10. In a filling valve, a valve body having respective vent and filling passages, a valve slide movably connected to said valve body having respective vent and filling passages for simultaneous registration with said body passages in one adjusted position of said slide relative to said body, said respective vent and filling passages having substantially the same cross-sectional area and said vent passages having a longer dimension in the direction of relative movement between said body and said slide than said filling passages, whereby the vent is established before a filling operation begins.

15. In a filling valve, a valve body having a flat face into which respective vent and filling passages open, a valve slide movably connected to said valve body having a flat face for sliding engagement with said body face and having respective vent and filling passages opening into the face thereof for cooperation with the similar body passages, said slide having a bore extending from a substantially semi-spherical recess at one end of said slide and terminating in a portion of a reduced diameter, and a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore.

20. In a filling valve, a valve body having respective vent and filling passages, a valve slide movably connected to said valve body having respective vent and filling passages for cooperation with the similar body passages, said slide having a bore extending from a substantially semi-spherical recess at one end of said slide and terminating in a portion of a reduced diameter, and a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore.

25. In a filling valve, a valve body having a flat face into which respective vent and filling passages open, a valve slide normally connected to said valve body having a flat face for sliding engagement with said body face and having respective vent and filling passages opening into the face thereof for cooperation with the similar body passages, said slide having a bore extending

from a substantially semi-spherical recess at one end of said slide and terminating in a portion of a reduced diameter, and a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore, said slide having an enlarged chamber around said tube at the top of said bore portion of larger diameter.

30. In a filling valve, a valve body having respective vent and filling passages, a valve slide movably connected to said valve body having respective vent and filling passages for cooperation with the similar body passages, said slide having a bore extending from a substantially semi-spherical recess at one end of said slide and terminating in a portion of a reduced diameter, and a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore, said slide having an enlarged chamber around said tube at the top of said bore portion of reduced diameter.

35. In a filling valve, a valve body having a flat face into which respective vent and filling passages open, a valve slide movably connected to said valve body having a flat face for sliding engagement with said body face and having respective vent and filling passages opening into the face thereof for cooperation with the similar body passages, said slide having a bore extending from a substantially semi-spherical recess at one end of said slide and terminating in a portion of a reduced diameter, a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore, and a substantially semi-spherical float movably supported by said tube for closing the vent passage therethrough.

40. In a filling valve, a valve body having respective vent and filling passages, a valve slide movably connected to said valve body having respective vent and filling passages for cooperation with the similar body passages, said slide having a bore extending from a substantially semi-spherical recess at one end of said slide and terminating in a portion of a reduced diameter, a tube secured in and communicating with the bore portion of reduced diameter and terminating in a substantially semi-spherical shell spaced from the wall of said semi-spherical recess to provide a part of said slide vent passage within said tube and a part of said slide filling passage exteriorly of said tube and within said bore, and a substantially semi-spherical float movably supported by said tube for closing the vent passage therethrough.

45. In a filling valve for selective use in filling under pressure, under vacuum, and with an open tank; a valve body having vent and filling passages therein, a valve slide associated with said valve body and having vent and filling passages therein for registration with said similar body passages when said valve slide is in filling posi-

- tion relative to said valve body, and liquid release passages in said valve body for selectively effecting communication between said vent and filling passages of said slide and the atmosphere in the valve closing position of said valve slide.
12. In a filling valve for selective use in filling under pressure, under vacuum, and with an open tank; a valve body having vent and filling passages therein, a valve slide associated with said valve body and having vent and filling passages therein for registration with said similar body passages when said valve slide is in filling position relative to said valve body, liquid release passages in said valve body for selectively effecting communication between said vent and filling passages of said slide and the atmosphere in the valve closing position of said valve slide, and float means for closing the lower end of said slide vent passage by operation of liquid rising in the container being filled.
10. 13. In a filling valve for selective use in filling under pressure, under vacuum, and with an open tank; a valve body having vent and filling passages therein, a valve slide associated with said valve body and having vent and filling passages therein for registration with said similar body passages when said valve slide is in filling position relative to said valve body, liquid release passages in said valve body for selectively effecting communication between said vent and filling passages of said slide and the atmosphere in the valve closing position of said valve slide, a float for closing said slide vent passage by operation of liquid rising in the container being filled, and means mounting said float on said slide to enable removal thereof when desired.
15. 14. In a filling valve for selective use in filling under pressure, under vacuum, and with an open tank; a valve body having vent and filling passages therein, a valve slide associated with said valve body and having vent and filling passages therein for registration with said similar body passages when said valve slide is in filling position relative to said valve body, and liquid release 20. passage means in said valve body for selectively effecting communication between said vent and filling passages of said slide and the atmosphere in the valve closing position of said valve slide.
25. 15. In a valve for filling cans or the like by a gravity flow of liquid from a tank, a valve body having a flat face, filling passage means leading from said face to said tank, vent passage means 25. leading from said face to said tank and terminating above the level of liquid therein, a valve slide movably connected to said valve body and having a flat face for cooperative sliding engagement with said body face, filling passage means 30. extending from the lower end of said valve slide to the flat face thereof, said filling passage means having an annular discharge opening at said lower end for directing an annular curtain of liquid against the wall of the can, vent passage 35. means extending from the lower end of said valve slide to the flat face thereof, spring means urging said slide downwardly with respect to said body to maintain the respective filling and vent passages out of communication, and a can lift ring 40. on said valve slide for engagement by a can to effect lifting of said slide to establish communication between the respective similar passage means of said valve slide and said valve body, whereby to enable a gravity flow of liquid from 45. said tank to the can.

CHARLES E. KERR.
